BUMPER JACK

Leonard D. Nilson, Wayzata, Minn., assignor to
 Vulcan Manufacturing Co., Inc., St. Paul,
 Minn., a corporation of Minnesota

Application March 23, 1937, Serial No. 132,565

7 Claims. (Cl. 254—93)

An object of my invention is to provide a bumper jack of simple, durable and inexpensive construction.

A further object is to provide a jack structure 5 of post-like construction having an operating member extending from the upper end thereof and reciprocable vertically, lifting means being provided within the post-like structure which is vertically slidably relative thereto and has a lifting sleeve telescopically movable on the exterior of the post-like structure, a hook clamp being adjustable on this lifting sleeve and being adaptable for engaging the bumper of an automobile for lifting the bumper and thereby one end of 10 the automobile.

Still a further object is to provide a bumper jack structure which has improved details of construction over the bumper jack disclosed in my Patent No. 2,064,445, dated December 15, 1936, 20 particularly with respect to improved mechanical details.

A further object is to provide in my improved jack a lifting sleeve which so telescopes with a vertical cylinder that in all positions of extension 25 the jack structure is extremely rigid.

Still a further object is to provide a steady sleeve for the piston rod which encloses the upper portion of the jack and telescopes over the exterior thereof to prevent any undesired bending 30 or binding of the piston rod of the pump within the jack.

Still a further object is to provide a novel intake and outlet valve arrangement including an intake valve which is readily operable in one 35 position of the pump of the jack to release the oil pressure within the jack, screw threaded means being provided for association and operation after the pressure has been released, the operation of the screw threaded means opening the 40 outlet valve to permit the jack to lower.

Still a further object is to provide means for sealing the jack against undesired leakage of oil therefrom when the jack is to be placed in the tool box.

Another object is to provide an automatic release means in the jack to prevent over extension thereof and consequent damage to the jack by bending of the tubular telescoping parts thereof.

With these and other objects in view, my invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of a bumper jack structure embodying my invention and showing it cooperating with a bumper bar.

Figure 2 is an enlarged sectional view on the line 2—2 of Figure 1 showing the lifting means 5 adjacent lowered position, portions of the structure being broken away to conserve space on the drawing, and such portions being indicated at a and b in Figure 2 which correspond to the portions within the brackets 2a and 2b of Figure 1. 10

Figure 3 is a similar sectional view showing the parts in a different position.

Figure 4 is a sectional view on the line 4—4 of Figure 2 showing a plan view of the intake valve.

Figure 5 is a sectional view on the line 5—5 of 15 Figure 1 showing a foot for the jack which is secured thereto by a ball and socket connection; and

Figure 6 shows a modified valve mechanism.

On the accompanying drawing I have used the 20 reference numeral 10 to indicate a base or foot for my jack structure. It is provided with a plurality of prongs 12 surrounding a ball seat 14. A ball 16, which forms the lower head of a lift cylinder 18, is seated in the seat 14. During assembly, after the ball is so seated, the prongs 12 are bent inwardly as clearly shown in Figures 1 and 5 to retain the ball against displacement from the seat thereafter.

The prongs 12 are spaced so that notches are 30 provided between them which permit the foot 10 to be swung to the dotted position shown in Figure 2, when it is desirable to place the jack in the tool box.

The lifting cylinder 18 has telescopically mounted thereon a lifting sleeve 20. A packing nut 22 is provided at the lower end of the lifting sleeve 20 to prevent escape of oil. Within the lifting cylinder 18 I provide a cup leather lifting piston 24 connected with a tubular lifting piston rod 26. 40 The upper end of the rod 26 is connected by a head 28 to the upper end of the lifting sleeve 20, whereby the two are simultaneously movable with the lifting piston 24 relative to the lifting cylinder 18. A clamp hook 30 is vertically slidable on the lifting sleeve 20, this being a split band of the ordinary type having a clamp bolt 32 for positively positioning it relative to the sleeve 20. It is provided with a hook 34 adapted to engage a bumper bar or bumper supporting bar 50 36 of an automobile as shown in Figure 1. The lifting cylinder at its lower end has a removable plug 19 for permitting introduction of oil from an oil can if any is lost by leakage.

For raising the piston 24 and thereby the clamp 55

hook 30, I provide a pump structure which will now be described.

A fitting 38 extends upwardly from the cup leather piston 24 and terminates in a head 40 which connects to the lower end of the lifting piston rod 26. The spaces between the cylinder 18 and the sleeve 20, within the cylinder 18 and within the tubular lifting piston rod 26, constitute a reservoir for oil. The oil has been omitted from the drawing to avoid confusion of details.

Ports 42 and 44 serve to communicate the reservoir spaces with each other. The lower end of the member 40 constitutes an intake valve seat indicated at 46. An intake valve 48 having a disk-like upper surface 50 is provided, which surface normally is seated against the seat 46 by a spring 52. The intake valve 48 has a pair of these disks which, as shown in Figure 4, are of hexagonal shape so oil can readily pass their peripheries. An outlet valve 54 of the ordinary ball type is provided within the lower end of the fitting 38. It is normally seated by a spring 56. Extending upwardly from the head 40 and arranged within the lifting piston rod 26 is a pump cylinder 58. A pump plunger 60 is reciprocable therein.

The intake valve 48 of Figure 2 may be modified as in Figure 6, showing a single disk 50' on the valve 48' and a guide sleeve 51 telescoping over a pump plunger 60'. The plunger 60' has a stem 61 to engage the ball valve 54 instead of a stem 48 for this purpose, as shown in Figure 3.

Returning to Figure 2, the upper end of the plunger 60 extends through a packing 62 in the head 28 and terminates in a head 64 relative to which it is screw threadedly mounted for adjusting purposes.

A countersunk lock nut for the plunger 60 is indicated at 66. In Figure 2 the plunger 60 is shown in its lowered position. During operation it extends some distance out of the packing 62 and to reinforce it against bending, I provide a steady sleeve 68 connected with the head 64 and telescoping over the lifting sleeve 20.

From the construction of the parts just described, it will be obvious that upon reciprocation, the plunger 60 will, upon upward movement when the intake valve 48 is seated, produce a vacuum between the seat 46 and the outlet valve 54. This pulls the intake valve 48 off its seat so that oil will be drawn downwardly through ports 70 in the head 40, and then upwardly into the pump cylinder 58. On the down stroke the valve 48 will first be closed, and thereafter the oil will be forced through the outlet valve 54 into the lifting cylinder 18 below the lifting piston 24, thus forcing it upwardly. Continued reciprocation of the plunger 60 will cause the jack to raise its supporting hook 34 until the piston 24 passes the port 44, whereupon upward movement of the jack is limited because any oil pumped to the lifting cylinder thereafter will by-pass back to the reservoir space between the cylinder 18 and the sleeve 20. This prevents excessive extension of the jack. Due to the disk-like character of the valve 48 and to its large size, but slight vacuum is needed to unseat it on the up stroke of the plunger 60 when the oil is thick during cold weather.

When it is desired to lower the jack the plunger 60 is moved to its downward limit of movement shown in Figure 2, which opens the intake valve 48, thus relieving the pressure on the oil caused by the piston 24 supporting the weight of the automobile. Thereafter the outlet valve 54 may

be opened for permitting the oil below the piston 24 to flow back into the reservoir spaces as a result of the weight of the automobile forcing the piston 24 downwardly. Opening the valve 54 is accomplished by a screw threaded connection indicated at 72 which assumes coacting relationship only upon clockwise rotation of the head 64 after the position of Figure 2 is reached.

Figure 3 illustrates the parts having been rotated for pushing the outlet valve 54 off its seat to permit lowering of the jack. By the use of the screw threaded connection a very fine adjustment of the valve 54 can be secured for either slow or fast lowering of the jack as desired.

After the jack has been used, the head 64 can be further rotated so that a gasket washer 74 therein will engage the upper end of the head fitting 28 to provide an additional insurance against leakage of oil from the jack around the pump plunger 60.

During pumping operations excessive outward movement of the plunger 60 is prevented by a collar 61 thereon, the inner end of the head 28 acting as a stop therefor.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a hydraulic jack structure, a cylinder, a lifting member slidable longitudinally relative thereto, lifting means within said cylinder and having an operating handle projecting therefrom, said operating handle being reciprocable for lifting operations, said lifting means including a pump cylinder, a disk-like intake valve, an outlet valve and a pump plunger, said pump plunger being operatively connected with said operating handle, said intake valve being engaged and opened by said pump plunger at one limit of its reciprocating movement and a screw threaded connection between said operating handle and said lifting member, associable and operable after such limit of movement has been reached, to open said outlet valve.

2. For a hydraulic jack having a lifting member and lifting means having an operating handle projecting from said lifting member, said operating handle being reciprocable for lifting operations and said lifting means including a pump cylinder, intake and outlet valves and a pump plunger and said pump plunger being operatively connected with said operating handle; said intake valve being engaged and opened by said pump plunger at one limit of its reciprocating movement and having an extension, and a rotatable screw-threaded connection between said operating handle and said lifting member, associable and operable after such limit of movement has been reached, to cause said extension to open said outlet valve.

3. In a jack of the character described, a vertical cylinder, a lifting sleeve slidable longitudinally relative thereto, lifting means comprising a lifting piston operatively connected with said lifting sleeve a pump to raise said lifting sleeve and including intake and outlet valves an operating and release rod for said pump extending from the upper end of said lifting sleeve and a screw-threaded connection between said rod and said lifting sleeve, associable after the rod has been reciprocated to its lowermost position and

thereby opened said intake valve and thereafter operable to effect release action by opening said outlet valve upon rotation of the screw threaded connection.

5. For a jack of the character described having a lifting sleeve slidable longitudinally relative thereto and lifting means for said lifting sleeve and comprising a lifting piston, a pump for pumping oil and an operating member for said pump, 10 said pump including intake and outlet valves and a pump plunger; said pump plunger being operable to engage and open the intake valve at the lower limit of reciprocation of the pump plunger and to thereafter cause the intake valve to engage and open the outlet valve upon rotation 15 of the pump plunger.

15. In a jack of the character described, a vertical support, a lifting sleeve slidable telescopically thereon, lifting mechanism contained within 20 said sleeve and operatively connected thereto and an actuating sleeve for said lifting mechanism operatively connected thereto and slidable telescopically of said lifting sleeve.

6. In a jack of the character described, a vertical support, a lifting sleeve slidable telescopically thereon, lifting mechanism contained within said sleeve and operatively connected thereto and an actuating sleeve for said lifting mechanism 5 operatively connected thereto and slidable telescopically of said lifting sleeve whereby sliding movement of the actuating sleeve functions to operate the lifting mechanism for raising the lifting sleeve.

10. 7. In a jack of the character described, a vertical support, a lifting sleeve slidable telescopically relative thereto, lifting mechanism for operating said lifting sleeve, said lifting mechanism being operatively connected with said lifting sleeve 15 and an actuating sleeve for said lifting mechanism operatively connected thereto and slidable telescopically of said lifting sleeve whereby sliding movement of the actuating sleeve functions to operate the lifting mechanism for elevating the 20 lifting sleeve relative to the vertical support.

LEONARD D. NILSON.
